United States Patent Office

Des. 195,175
Patented May 7, 1963

195,175

PLAY POOL OR SIMILAR ARTICLE

Leonard E. Greenberg, West Hartford, Conn., assignor to Coleco Industries, Inc., Hartford, Conn., a corporation of Connecticut

Filed Oct. 31, 1962, Ser. No. 72,322

Term of patent 14 years

(Cl. D34—5)

FIG. 1

FIG. 3

FIGURE 1 is a perspective view of a play pool or similar article showing my new design;

The dominant features of my design reside in the full-line portions of the drawings.

I claim:

The ornamental design for a play pool or similar article, as shown and described.
